UNITED STATES PATENT OFFICE.

BURT R. VAN VALKENBURG, OF OAKLAND, CALIFORNIA.

VALVE-CHEST.

1,328,796.

Specification of Letters Patent.

Patented Jan. 20, 1920.

Application filed May 17, 1916. Serial No. 98,184.

To all whom it may concern:

Be it known that I, BURT R. VAN VALKENBURG, a citizen of the United States, residing at Oakland, in the county of Alameda 5 and State of California, have invented certain new and useful Improvements in Valve-Chests, of which the following is a specification.

This invention relates to improvements in 10 valve chests for pneumatically operated musical instruments and has for its object the construction of a chest, which is simple in construction and effective in operation.

Another object of the invention is to construct the chest so that the valves and pneumatics are readily accessible and removable for repairs and adjustment.

Another object of the invention is to construct the chest so that there are no air passageways across the joints between the several layers composing the same.

With these and other objects in view my invention consists in the novel construction, combination and arrangement of parts herein 25 illustrated and more specifically pointed out in the appended claims.

Reference being had to the accompanying drawing forming a part of this specification,

Figure 1 is a view in section through the 30 upper part of the piano showing the manner in which my improved chest is installed therein.

Fig. 2 is an enlarged transverse sectional view through my improved chest.

Fig. 3 is a view in elevation of the inside 35 of the chest, a front cover plate being removed.

Fig. 4 is a view in section on 4—4 of Fig. 2.

40 Denoting corresponding parts in the several views by the same numerals of reference, 1 denotes the piano action, and 2 my improved chest in general. The usual perforated music roll is denoted by 4, and this 45 passes over the tracker bar 3, having openings 5', connected by tubular pipes 5, with certain passageways 12 in the chest 2. This chest extends the full width of the piano and comprises two or more vertical strips as 50 carrier strip 6 and front strip 7, to which are attached end plates 8, having suitable fastening means 9, by which the chest is attached to the piano case. Between strips 6 and 7, is a cavity 10 connected by a pipe 11 55 to the suitable means for maintaining a vacuum.

On the back of strip 6 is mounted a plurality of triangular blocks 13 attached to the strips by means of screws 14, each block being removable independent of any other 60 block. These blocks are preferably arranged in staggered relation, as shown at Fig. 3. The distance between their centers being the same as the distance between each note sounding mechanism. 65

On the under side of each of these blocks is mounted a flexible bellows 15, having the movable side 16, from which extends an arm 17. To these arms are pivotally connected rods 18, which extend upwardly and are 70 there in threaded engagement with the contact members 19. These members are slidably mounted in a guide bar 20, held to the end members of the chest by means of brackets 21, and below this strip are blocks 23 75 adjustably mounted on the rods and having the cushioning washers 24. These blocks are adapted to contact with the under side of guide bars 20 and thereby limit the upward movement of contact members 19. The 80 downward movement of the movable side of the bellows is limited by a cushioning pad 22 on the top of the block 13 next below and for the bottom bellows by a strip 22' extending from one end plate 8 to the other 85 and provided with a suitable cushioning pad.

Member 19 contacts with some portion of the piano action, so that the collapsing of any bellows 15 operates the corresponding 90 note sounding mechanism.

At the sides and communicating with recess 28 are passageways 50, which extend through the block 13 to the interior of the 95 bellows.

Extending inwardly from the upper surface of the respective blocks 13 are two recesses 25 and 26 spaced so as to provide a division wall 27 therebetween. A recess 28 is provided in the base of each of the 100 blocks 13, and in the strip 6 are openings 29, with which the recesses 28 align when the blocks are in position. A passageway 30 furnishes communication between recess 28 and recess 26, smaller in diameter than 105 the recess 28, providing a shoulder 29' which forms a valve seat. Covering the inner end of opening 29 is provided a disk 31, having an opening 31', forming a valve seat, and, across this disk is a guide strip 32 through 110 which extends a valve stem 33, the inner end of which is slidably mounted in the di-

vision wall 27. Between 31 and the shoulder 29 the valve stem is provided with two spaced apart disks denoted 34 and 35, the former of which is adjustably mounted on 5 the threaded portion of the stem while the latter is held in place between two fixed collars. In alinement with each of the triangular blocks there is a cell 40 in the inner wall of strip 7, which cell is separated 10 from the vacuum cavity by the flexible diaphragm 40', and against this diaphragm rests the disk 36, adjustably attached to the end of valve stem 33. The construction just described forms a secondary valve by which 15 the interior of the bellows is placed either in communication with the vacuum cavity or atmospheric pressure.

In the inner face of the upper end of strip 6 is a plurality of cells 42, there being one 20 of these cells for each cell 40. The cells are separated from the vacuum cavity by a flexible diaphragm 47, having attached on the vacuum side disks 49. Each of these cells is connected by a passageway 43, with the corresponding tubular member 5 leading from 25 an opening of the tracker bar. A bleed opening 44 is provided between the vacuum cavity 10 and passageway 43, thereby maintaining this passageway and the tubular member 5 in an exhausted condition, while 30 the opening of the tracker bar is closed.

In strips 7 in alinement with the axis of each cell 42 is a transverse passageway 45 connected by passageway 46' with the cell 35 40. The outer end of passageway 45 is closed by a flexible strip 46 and extending between the latter and the flexible diaphragm 47 of cell 42 is a pin 48. By this construction are formed primary valves extending through block 13 through which the 40 corresponding secondary valves above described are governed.

The operation is as follows:

When one of the openings 5' in the tracker 45 bar is uncovered, air is admitted through the tubular connecting member 5 and passageway 43, into the cell 42. Diaphragm 47 thus having pressure on one side and vacuum on the opposite side is moved outwardly causing 50 the disks 49 to seat on the face of strip 7 and so close the inner end of passageway 45, while the pin 48 lifts the flexible strip 46 from the outer end, admitting atmospheric pressure through the passageway 46' 55 into the cell 40. This cell having atmospheric pressure in one side and vacuum in the other, the diaphragm is pressed outwardly causing the disk 34 to close the opening 30 to the atmospheric pressure and the disk 35 to open passageway to the vacuum 60 through the valve seat 31, thus permitting the air to be exhausted from the corresponding bellows 15. The recess 25 is a convenient arrangement to provide a clearance

for the end of valve stem 33. The bellows 65 is thus collapsed and the corresponding note is sounded. It will be noted that with my improved construction there are no long passageways within the chest itself in which it is necessary to exhaust between each 70 sounding of a note. Also that there are no air passageways across from one strip to the other, making joints at which leakage is apt to occur.

It will also be noted that by the removal 75 of plate 7 all parts of the valves are readily accessible. If any pneumatic becomes out of order the same may be removed without the disturbance of any other. The bleed opening may be easily reached for cleaning, 80 thus providing a chest which is effective in operation as well as convenient to maintain any effective operating condition.

I claim as new and wish to cover by Letters Patent:

1. A valve chest of the character described comprising a carrier strip and a front strip secured together in spaced relation to provide a vacuum chamber between them, pneumatic carrier blocks attached to the external face of said carrier strip, pneumatics attached to the respective blocks, each block having the end which abuts the carrier strip provided with a recess communicating with a passage way leading to the atmosphere, 90 said carrier strip having openings registering with said recesses to provide passage ways leading from said recesses to the vacuum chamber, secondary valves mounted to selectively place said recesses in communication either with the atmosphere or with the vacuum chamber, primary valves controlling the operation of the last mentioned valves, and means for operatively attaching said primary valves to said carrier strip 95 in positions to be exposed by removal of said front strip.

2. A valve chest of the character described comprising a carrier strip and a front strip secured together in spaced relation to provide a vacuum chamber between them, pneumatic carrier blocks attached to the external face of said carrier strip, pneumatics attached to the respective blocks, each block having the end which abuts the carrier strip 110 provided with a recess communicating with a passage way leading to the atmosphere, said carrier strip having openings registering with said recesses to provide passage ways leading from said recesses to the vacuum chamber, secondary valves mounted to selectively place said recesses in communication either with the atmosphere or with the vacuum chamber, the front strip being provided with recesses alined with the recesses in said blocks and said carrier strip, diaphragms covering the recesses in the front strip, means connecting said dia-

phragms with said valves, primary valves controlling the admission of air to and exhaustion of air from the recesses of the front strip, and means for operatively attaching said primary valves to said carrier strip in position to be exposed by removal of said front strip.

3. A valve chest of the character described comprising a carrier strip and a front strip secured together in spaced relation to provide a vacuum chamber between them, pneumatic carrier blocks attached to the external face of said carrier strip, pneumatics attached to the respective blocks, each block having the end which abuts the carrier strip provided with a recess communicating with a passage way leading to the atmosphere, said carrier strip having openings registering with said recesses to provide passage ways leading from said recesses to the vacuum chamber, secondary valves mounted to selectively place said recesses in communication either with the atmosphere or with the vacuum chamber, the front strip being provided with recesses alined with the recesses in said blocks and said carrier strip, diaphragms separating the last mentioned recesses from the vacuum chamber, the stems of said secondary valves resting against said diaphragms, the carrier strip having cells and tracker bar ducts communicating therewith, flexible diaphragms attached to the carrier strip and covering said cells, said front strip having passage ways in alinement with the axes of said cells and extending to the atmosphere, ducts connecting said passage ways with the recesses in the front strip, primary valves attached to said cell diaphragms in position to close the inner ends of the passage ways in the front strip, flexible vent caps positioned to close the outer ends of said passage ways, and pins extending from said primary valves and engaging said vent caps, all of

said valves being positioned to be exposed 45 by removal of said front strip.

4. A valve chest of the character described comprising a carrier strip having openings therein, carrier blocks attached to said strip, pneumatics supported by said blocks and communicating with said openings, primary valves operatively supported by said carrier strip, secondary valves controlling said pneumatics and supported and guided by said carrier strip and said blocks, and a 55 front strip removably attached to the carrier strip, said valves being so positioned that removal of the front strip will expose them, a vacuum chamber being provided between said front strip and said carrier 60 strip.

5. A valve chest of the character described comprising a carrier strip having openings therein, primary valves controlling the operation of the secondary valves, and a front 65 strip removably attached to the carrier strip, said primary and said secondary valves being positioned to be exposed by removal of the front strip, a vacuum chamber being provided between said front strip and 70 said carrier strip.

6. A valve chest of the character described comprising a carrier strip having openings therein, pneumatic carrier blocks abutting the outer face of said strip, securing devices for said blocks passed through said strip from the inner face thereof, pneumatics supported by said blocks and communicating with said openings, secondary valves controlling said pneumatics, and a front 75 strip removably attached to the carrier strip, said secondary valves and the fastening devices for the carrier blocks being in a position to be exposed by removal of the front strip, a vacuum chamber being provided between said front strip and said carrier strip. 80

In testimony whereof I affix my signature.
BURT R. VAN VALKENBURG.
